FOLDED PAPER BOX CONSTRUCTION

Joseph A. Pidgeon, Salem, Ohio, assignor to The Budget Press, Salem, Ohio, a partnership

Application June 12, 1952, Serial No. 293,061

3 Claims. (Cl. 229—8.5)

The invention relates to a folded paper box construction and more particularly to a coin bank or mite box formed of cardboard in one piece in a simple manner which may be inexpensively and easily fabricated, quickly assembled and efficiently used as a receptacle for the accumulation of coins for charitable or other purposes, such as for saving money for special church offerings.

Heretofore, cardboard mite boxes have been made of two general types, either preassembled or assembled by the user. The latter type ordinarily includes assembly tabs which are inserted in the box coin opening and engaged against the inside surface of the coin opening wall to maintain the folded cardboard portions in box form. This construction has several disadvantages. The box frequently tears open at the ends of the coin slot from the pull of the inserted tabs which maintain the box assembled; and coins may be removed from the coin slot rather easily.

The prior preassembled form of cardboard mite box construction overcomes some of the foregoing disadvantages but normally involves two or more pieces of cardboard or paper in the construction and assembly thereof and particularly when special printing or coloring is to be applied to certain faces or surfaces of the assembled box. Moreover, prior preassembled mite box constructions involve considerable waste or scrapping of cardboard when cutting the same from standard sized cardboard sheets to obtain a maximum sized box, thus increasing the cost of the box.

Maximum strength and ruggedness can be provided in a cardboard mite box construction if heavy cardboard is used and if a number of the walls of the box are formed as double thickness walls. Heretofore in preassembled cardboard box construction, difficulty has been encountered in using heavy cardboard because the same is apt to crack if bent beyond 90° along score lines during assembly. Certain prior preassembled boxes, assembled of either one or more pieces, have been subject to this cracking difficulty and have not provided a maximum number of double thickness box walls for strength and ruggedness.

Accordingly, it is a general object of the present invention to provide an improved one piece, cardboard mite box construction of the preassembled type having great strength, rigidity and ruggedness.

Furthermore, it is an object of the present invention to provide an improved preassembled, one piece, cardboard mite box construction with assembly tabs arranged such as to limit all bends to 90° so as to avoid cracking of the stock, particularly if clay coated box board is used as the stock from which the box is formed.

Also, it is an object of the present invention to provide an improved preassembled, one piece, cardboard mite box construction which has a tab arrangement facilitating the rapid hand assembly thereof.

Likewise, it is an object of the present invention to provide a new preassembled, folded, one piece, cardboard mite box construction which has great resistance to deformation for surreptitious opening of the box, by providing a tab arrangement which results in tearing the box open for either authorized or unauthorized entry to the contents thereof.

Also, it is an object of the present invention to provide an improved preassembled, one piece, cardboard mite box construction in which a maximum number of blanks may be cut with minimum waste from standard sized sheets of cardboard stock.

2

Moreover, it is an object of the present invention to provide an improved preassembled, one piece, folded cardboard mite box construction which has great strength against twisting collapse of the box walls.

5 Also, it is an object of the present invention to provide an improved preassembled, folded, one piece, cardboard mite box construction which can be provided with two color printing on a plurality of the box walls without the necessity of applying a separate printed paper wrapping to the assembled box as has been usual in prior box construction.

Furthermore, it is an object of the present invention to provide an improved preassembled, one piece, folded cardboard mite box construction in which one continuous wrap or sleeve of cardboard is provided around four connected sides of the assembled box, and a second continuous wrap or sleeve of cardboard is provided at right angles to the first continuous wrap, also around four sides of the assembled box.

15 Finally, it is an object of the present invention generally to improve the construction and manufacture of folded cardboard mite boxes, and to obtain the foregoing desirata in a simple, effective and inexpensive manner.

20 25 These and other objects and advantages apparent to those skilled in the art from the following description and claims may be obtained, the stated results achieved, and the described difficulties overcome, by the discoveries, principles, products, combinations, subcombinations, parts and elements, which comprise the present invention, the nature of which is set forth in the following statement, a preferred embodiment of which—illustrative of the best mode in which applicant has contemplated applying the principles—is set forth in the following description, and which are distinctly and particularly pointed out and set forth in the appended claims forming part hereof.

25 The nature of the improvements in folded paper box construction of the present invention may be stated in general terms as preferably including a one piece, relatively heavy, cardboard blank cut and scored to form a base panel, an end panel projecting and foldable or hinged from one end edge of the base panel having a coin opening therein, an assembly tab projecting and bendable on a slotted line from the opposite edge of said end panel, foldable assembly tabs projecting from the side edges of said end panel, a second end panel projecting and foldable or hinged from the end edge of the base panel opposite the one end edge, a primary top panel projecting and foldable or hinged from the opposite edge of said second end panel, an assembly tab projecting and foldable from the outer edge of said primary top panel, other assembly tabs foldable and projecting from the side edges of said second end panel, a primary side panel projecting and foldable or hinged from one side edge of the base panel, a second side panel projecting and foldable or hinged from the opposite side edge of said base panel, a secondary top panel projecting and foldable or hinged from the opposite edge of said second side panel, a secondary side panel projecting and foldable or hinged from the opposite edge of said secondary top panel, glued areas on the inner faces of said primary side panel, said secondary top panel and said secondary side panel, said secondary top and side panel glued areas adhering to the outer surfaces of the primary top and side panels, and the folds or hinged joints between adjacent panels being limited to 90° bends.

30 35 40 By way of example, a preferred embodiment of the improved folded paper box construction is illustrated in the accompanying drawings forming part hereof wherein,

45 50 55 Figure 1 is a plan view of a standard sized cardboard sheet illustrating two improved box blanks cut therefrom with minimum waste;

60 65 70 Fig. 2 is an enlarged plan view of the opposite or inside face of one of the blanks illustrated in Fig. 1;

75 80 Fig. 3 is a perspective view showing certain of the panels of the blank of Fig. 2 folded in a primary stage of assembly;

85 Fig. 4 is a view similar to Fig. 3 showing the further folding and assembly of certain of the panels;

Fig. 5 is a view similar to Fig. 4 showing the completed assembled box;

Fig. 6 is a lateral section looking in the direction of the arrows 6—6, Fig. 5; and

Fig. 7 is a longitudinal section looking in the direction of the arrows 7—7, Fig. 5.

Similar numerals refer to similar parts throughout the various figures of the drawings.

Although the improved box of the present invention generally illustrated at 1 in Fig. 5 may be made of any one of a number of types of relatively heavy cardboard, it is preferred to fabricate the same of clay coated box board stock so as to provide smooth finished surfaces for the interior and exterior of the box and so as to provide for printing in one, two or more colors, if desired, directly on certain surfaces of the blank which become exterior panel surfaces of the completed box in order to eliminate the necessity of furnishing and assembling a second printed paper wrap for the box where color printing on certain surfaces of the completed box may be desired.

Clay coated box board is normally furnished by paper mills in standard sized sheets, one standard size being a 22" x 28" sheet. This standard size sheet may be cut without waste to form four 11" x 14" cardboard blanks, one of such blanks being indicated at 2 by the outline in Fig. 1. Two box blanks generally indicated at 3 in Fig. 1 for forming the improved box may be cut from the cardboard blank 2 with minimum waste. In the various figures of the drawing, the cut edges of the various panels and tabs of the box blanks 3 are shown in full lines, while scoring to form the bend or fold or hinge lines between adjacent panels are indicated in dot-dash lines.

In Fig. 1, the outer faces or surfaces of the box blanks 3 are shown, certain panel surfaces of which ultimately provide outside surfaces of the assembled box 1. In Fig. 2, a box blank 3 is shown upside down with respect to blanks 3 of Fig. 1 to display the inside faces or surfaces of the various panels of the blank.

Referring to Fig. 2, a base panel is indicated at 4 bounded by scoring or fold lines 5, 6, 7 and 8. An end panel 9 extends from one end edge of base panel 4 at fold line 6 and an assembly tab 10 projects from the opposite edge of end panel 9 at fold line 11. The blank 3 is cut entirely through at 12 along a central portion of the fold line 11 for a purpose to be later described. A coin slot 13 is cut in end panel 9; an assembly flap 14 and a primary side wall panel 15 project from the opposite end fold lines 16 and 17 respectively of end panel 9.

Another end panel 18 bounded by fold lines 8, 19, 20 and 21 projects from fold line 8 of base panel 4 and a primary top panel 22 projects from fold line 20 of end panel 18. At the extreme end of primary top panel 22, an assembly tab 23 projects from fold line 24.

A primary side panel 25 projects from fold line 5 at one side edge of base panel 4 while a secondary side panel 26 projects from the fold line 7 at the other side edge of base panel 4. At the opposite edge of panel 26, a secondary top panel 27 projects from fold line 28, and another secondary side panel 29 projects from the opposite edge of panel 27 at fold line 30. Assembly tabs 31 and 32 also project from fold lines 21 and 19 respectively of end panel 18.

In assembling the improved box 1 from the improved one piece box blank 3, end panels 9 and 18 are first bent 90° upwardly as shown in Fig. 3 on fold lines 6 and 8, respectively, and at the same time the tabs or panels 14, 15, 31 and 32 are folded 90° inwardly along fold lines 16, 17, 21 and 19, respectively, also as shown in Fig. 3. The folding of the tabs 14, 15, 31 and 32 at the same time that panels 9 and 18 are folded prevents the folds along lines 6 and 8 from being made beyond 90° thus avoiding cracking of the stock at the fold lines. Panel 15 is received to underlie tab 32 during the preliminary folding illustrated in Fig. 3 for a purpose to be later described.

Referring to Figs. 3 and 4, the next operations in completing the assembly of the box 1 are to turn tab 10 inward along fold line 11, to bend panel 22 downward on fold line 20, and to bend tab 23 down on fold line 24, tab 23 being inserted through slit 12 of fold line 11 so as to enter the interior of the box as illustrated in Fig. 4. It is noted that the length of tab 23

is such that it extends across the coin opening 13 thereby providing a closure for the opening 13 which will yield to permit the insertion of a coin but which prevents coins from dropping out of opening 13 if the box is shaken.

At this stage of the assembly, there is a complete assembled six-sided box form with single thickness walls for each of the six panels of the box excepting for the space 33 between the ends of tabs 31 and 14 as indicated in Fig. 4. Moreover, hinge connected panels 9, 4, 18 and 22 with interengaged tabs 23 and 10 form a complete sleeve or longitudinal wrap of connected walls around four sides of the box in one direction. Furthermore, the lower side edges of tabs 14, 31 and 32 and of panel 15 engage the inner face of base panel 4 along fold lines 5 and 7 so as to prevent bending of the stock on fold lines 6 and 8 beyond 90°. Finally, primary side panel 15 extends the full length of the box side wall and its free end abuts the inner face of panel 18 adjacent fold line 19 and underlying tab 32.

The cooperative arrangement of the tabs and panels thus far described, provide complete rigidity and stability to the box form in the stage of assembly illustrated in Fig. 4, it being noted that the assembly of panel 15 within tab 32, as illustrated in Fig. 3, prevents coins from being shaken out of the box around the free end of panel 15 which abuts against the inner face of end panel 18.

Prior to folding and assembling the box, the inner faces (the upper faces viewing Fig. 2) of panels 25 and 29 and of a portion at least of panel 27 are coated with an adhesive, gum or mucilage, as indicated by the stippling at 34 and 35 in Fig. 4, said stippling being omitted from Figs. 2 and 3 for simplification.

Following the stage of assembly illustrated in Fig. 4, side panel 25 is bent upward on fold line 5 so that its gummed surface 35 adheres to the outer faces of tabs 31 and 14, and panels 26, 27 and 29 are bent on fold lines 7, 28 and 30 to wrap around the primary wrap so that the gummed area 34 on panel 27 adheres to a portion of the top face of panel 22 and the gummed area 34 on panel 29 adheres to the outer face of panel 25 thereby forming the completed box assembly 1 illustrated in Fig. 5.

Thus the hinge connected panels 25, 4, 26, 27 and 29 form a complete sleeve or lateral wrap around four sides of the box in another direction, with respect to the primary four-sided wrap of panels 9, 4, 18 and 22.

Each of the six panels or walls of the box 1 has great strength, stability and ruggedness by reason of its construction and cooperative relation relative to the other walls. Base panel 4 is of single thickness but is stiff and strong because of being hinge connected at each of its four sides to adjacent panels. Similarly end panel 18 is stiff and strong because of being hinge connected at each of its four sides to other panels or tabs even though panel 18 has only single thickness. The same comments apply to the other end panel 9 which also has only a single thickness wall.

The top of the box, however, has a wall of double thickness cardboard formed of primary top panel member 22 and secondary top panel member 27 glued thereto. One side of the box comprises a double thickness cardboard wall including primary side panel member 15 and secondary side panel member 26. The other box side wall is substantially a triple thickness wall formed first of tabs 31 and 14 to which primary side panel member 25 is glued, and finally secondary side panel member 29, which is glued to primary side panel member 25 as shown in Fig. 6.

When it is desired to provide color printing of one, two or more colors on the outer surfaces of the completed box 1, this may be accomplished by printing on the proper areas of the blank 2 prior to cutting the box blanks 3 therefrom. For example, the outer faces of panels 4, 26, 27 and 29 which form the top, bottom and side walls of the box may be printed directly in one color such as red or blue and printed matter may be impressed thereon to form the top, bottom and side walls of the box in one color and the two end walls in another color such as, for instance, the basic color of the card board stock which may be white.

The improved one piece box construction has a number of essential and new characteristics. Because of the particular arrangement of the tabs and panels, all bends

of the cardboard stock are limited to 90° which prevents the stock from cracking at the bends or hinge joints particularly if the stock is relatively heavy for strength or if it is formed of clay coated box board. The boxes may be quickly and easily assembled at a fabricating plant to make preassembled boxes. If it is attempted to gain access to the interior of the box surreptitiously to remove the contents thereof in an unauthorized manner by manipulation of the end wall 9, and tabs 10 or 23 must be torn loose. Further deformation of the end wall 9 is resisted by tab 14 and primary side panel wall 15. Panel wall 15 in extending full length of the box provides increased leverage resisting such deformation.

Furthermore, the extension of tabs 31 and 32 from end wall 18 and of tab 14 and panel 15 from end wall 9, 15 rather than from other panels or walls of the blank, provides increased resistance against twisting collapse of the box 1.

With the particular construction and arrangement of the box and its folded and connected panels and tabs, there is a minimum of waste in cutting the box blanks 3 from cardboard stock 2; and in the manner described, the improved construction enables two color printing to be applied to the box without resorting to the provision of an additional printed paper wrapping.

Accordingly, the present invention provides a new folded, preassembled, one piece, cardboard mite box construction which is inexpensive to construct and assemble, which involves a minimum waste in cutting box blanks from standard sized cardboard stock, which is stiff, strong and rugged against collapse, unauthorized opening and normal usage, which may be formed of clay coated box board without cracking and directly printed without applying a separate printed paper wrapper for color printing, and which is extremely durable and attractive in use.

In the foregoing description, certain terms have been used for brevity, clearness and understanding, but no unnecessary limitations are to be implied therefrom beyond the requirements of the prior art, because such terms are utilized for descriptive purposes herein and not for the purpose of limitation and are intended to be broadly construed.

Moreover, the description of the improvements is by way of example, and the scope of the invention is not limited to the exact details illustrated and described.

Having now described the various features, discoveries and principles of the invention, the construction and assembly of the new preassembled one piece cardboard mite box, and the new and advantageous results obtained thereby; the new and useful discoveries, principles, products, combinations, sub-combinations, parts and elements, and mechanical equivalents apparent to those skilled in the art are set forth in the appended claims.

I claim:

1. A coin-receiving box made of a relatively heavy, one-piece, cardboard blank cut, scored and folded to form bottom, top, two side and two end walls including a base panel, end panels hingedly connected to the base panel, a tab hinged to one end panel provided with a slot along its hinge portion, said end panel also being provided with a coin receiving slot centrally therein, a primary top panel hingedly connected to the other end panel and having a tab engaged in said slot, said tab extending beneath and slightly beyond said coin receiving slot, side flaps hingedly connected to opposite side edges of each end panel, a primary side panel hingedly connected to the base panel, a member hinged to the base panel comprising a side panel portion, a secondary top panel portion hinged to the side panel portion, and a secondary side panel portion hinged to the secondary top panel portion and overlapping the primary side panel, and adhesive means securing the secondary top and side panels to the primary top and side panels.

2. The construction defined in claim 1 in which one of the side flaps hinged to one of the end panels extends full length of the box and provides a primary side panel underlying the side panel portion of the member hinged to the base panel.

3. The construction defined in claim 1 in which one of the flaps hinged to one of the end panels extend full length of the box and is engaged beneath a flap hinged to the other end panel and underlies the side panel portion of the member hinged to the base panel.
